UNITED STATES PATENT OFFICE.

MARTIN L. BYRNE, OF SYRACUSE, NEW YORK.

COLLAPSIBLE TUBE.

Application filed July 31, 1924. Serial No. 728,302.

To all whom it may concern:

Be it known that I, MARTIN L. BYRNE, a citizen of the United States, residing at Syracuse, in the county of Onondaga and 5 State of New York, have invented certain new and useful Improvements in Collapsible Tubes, of which the following is a specification.

This invention relates to improvements in 10 collapsible tubes, of the type commonly employed for tooth-paste, shaving-cream, ointments, liquid-glue, and the like, and has for its primary object to eliminate the usual threaded necks and screw-caps of the older 15 tubes, and in lieu thereof to provide a container of the class, that opens for the dispensing of the contents, by the operator squeezing the body of the container, and wherein the discharge openings are closed 20 automatically when the pressure on the body is relaxed. A further object is to provide a collapsible tube whose discharge end comprises a relatively large normally open neck, which is formed with a dispensing slot and 25 also with means whereby a closure may be retained. A further object is to provide a novel cap for closing the neck, the said cap having L-shaped slots engaging the retaining means of the neck and having circumferential slots adapted to register with the 30 discharge opening of the neck, the said cap being arranged to telescope the neck and being movable longitudinally away from the body of the tube, for effecting the dispensing 35 of the contents, and said cap being movable towards the body of the tube for stopping the discharge of the contents automatically. A further object is to provide novel tension means for effecting the automatic closing 40 movement of the cap. And a further object is to provide means for limiting the linear as well as the rotatable movements of the cap, and for preventing the accidental release of the cap from the neck.

45 I attain these objects by the means set forth in the detailed description which follows, and as illustrated by the accompanying drawing, in which—

Figure 1 is a top end view of the tube. 50 Fig. 2 is a broken side elevation, showing the cap in closed position. Fig. 3 is a horizontal section, taken on line 3—3 of Fig. 4. Fig. 4 is a broken side elevation and partial central vertical section, the latter being taken on 55 line 4—4 of Fig 5. Fig. 5 is a top end view showing the tension strap shifted, as when

the cap is locked in the closed position. Fig. 6 is a broken side elevation and central vertical section, the latter being taken on line 6—6 of Fig. 1, showing the cap extended for 60 effecting the discharge of the contents of the tube. Fig. 7 is respectively a central vertical section and a side elevation of the cap, the section being taken on line 7 of the elevation. Fig. 8 is a broken side elevation of 65 the tube with the cap removed. And Fig. 9 is a partial elevation and partial central vertical section, showing modified tension means for closing the cap.

In the drawing, 2 represents the relatively 70 thin pliable cylindrical shell or body of the tube, 2' is the reduced tubular neck, which is joined to the body by a tapering portion 2^a. When the tube is constructed, both ends are normally open, and the paste or cream is 75 usually applied at the bottom end, after which the said end is closed and sealed in a well-known manner. The neck 2' is closed before the filling of the body by a hollow cap, which comprises outer and inner hollow 80 concentric tubular members 3—3', which are arranged to slidably telescope the neck 2', and the top of the cap is preferably formed with a central shallow depression *x*, as 85 shown in Figs. 1, 3, 4, 6 and 9. The open 85 end of the outer member 3 is preferably 90 beveled, as at 3^a, to conform to and fit the tapering portion 2^a, as shown in Figs. 2, 4 and 9. The inner member 3' is also internally beveled, as at 3^b. The angles of the 95 portions 2^a and 3^b are preferably relatively slight, in order to offer the least resistance to the movement of the contents of the tube towards the neck when the tube is compressed. The neck 2' is provided with a circumferential slot 2^b, for dispensing the paste or cream, and the members 3—3' of the cap are provided with similar slots 3^c—3^d, which register with each other. The slots of the 100 cap and neck are preferably disposed in different planes when the cap is in the closed position, for preventing the escape of the contents of the tube by leakage, as shown in Figs. 4 and 9. But when the cap is extended, as shown in Fig. 6, due to the displacement of the contents by the forcible collapsing of the body 2, the several slots 2^b, 3^c and 3^d are brought into registry, and a ribbon-like discharge of the contents is effected, as shown by the arrow in Fig. 6. 110 The cap is held in place and is allowed sufficient longitudinal movement on the neck

2' to effect the dispensing of the paste, by means of two diametrically opposed pins or gudgeons 4—4', which are permanently set in the walls of the neck 2', as best seen in Fig. 3. These pins project outwardly and engage and play in similar L-shaped slots 4^a—4^b, which are formed in the corresponding walls of the outer member 3 of the cap, as will be understood by consulting Figs. 1, 10 3, 4 and 7. The pins 4—4' are preferably disposed near the base of the neck, and when the cap is in the closed position (see Figs. 2 and 4), the said pins are positioned at the top of the vertical arms of the slots 4^a—4^b, in 15 readiness to traverse either the vertical or horizontal arms of said slots, owing to whether the cap is extended, as shown in Fig. 6, or rotated clockwise, as shown in Figs. 4 and 5, for disposing the pins in the 20 dead-end of the horizontal arms of the slots, which effects the locking of the cap against accidental movement longitudinally. This locking feature has the advantage of preventing loss or waste of the contents of the 25 container due to rough handling between the dispensing periods. The pins 4—4' are preferably provided with annular grooves 4^c (see Figs. 3 and 8), for attaching the ends 30 of a tension strap 5, which extends from the pins upwardly and across the top of the cap, as best seen in Figs. 1, 2, 4 and 5, and in order to prevent undue straining of the said strap when the cap is rotated to the extent allowed by the slots 4^a—4^b, the top of the cap 35 beyond the recess α is provided with similar radial grooves 5'—5^a, which receive and hold the medial portion of the tension strap in the proper position relatively to the pins, as shown in Figs. 1 and 5. Ordinarily, before 40 the cap is rotated in either direction, the operator grasps the strap 5 where it crosses the depression α and lifts and holds it clear of the grooves 5'—5^a, while he rotates the cap, and then lets the strap settle into the 45 adjacent groove that aligns with the pins 4—4'. The strap 5, which preferably consists of spring wire is formed with similar tension coils 5^c, which are positioned near its opposite ends. The vertical arms of the 50 slots 4^a—4^b are provided at their lower ends with flexible lugs 4^c, for preventing accidental release of the cap from the neck 2'. When the cap is made, these lugs are usually 55 bent outwardly for facilitating the free entrance of the pins 4—4', after which the lugs are bent towards each other for partially closing the slots, as shown in Figs. 1, 4 and 7.

In Fig. 9 I have shown a slight modification, which consists of inserting a rod 6 diametrically through the base of the neck of the tube, and then providing a single coil spring 7 having a plain portion 7', which passes through an opening in the head of the cap, the free end of said portion after-

wards being formed into a loop or head 7^a, which is disposed in the shallow recess α of the cap. The opposite end of the tension member 7 is formed into a hook 7^b which grips the rod 6. The spring 7 tends to pull 70 the cap downwardly and holds it resiliently in the closed position, the same as the strap 5. The modification has the advantage of disposing the tension means within the neck and cap, and requires less material and 75 labor for its construction and assembling.

Having thus described my invention, what I claim, is—

1. A collapsible tube having a normally open neck, said neck having a discharge 80 slot in one side, a cap for closing said neck, said cap comprising concentric cylindrical members which are spaced to receive therebetween the said neck, the said members having discharge slots in the corresponding 85 sides adapted to register with the slot of the neck when the cap is extended, and means for automatically restoring the cap to the closed position for stopping the discharge through said slots. 90

2. A collapsible tube having a normally open neck, said neck having a discharge slot and gudgeons below said slot, a cap for closing said neck, said cap comprising concentric tubular members which are 95 spaced to receive the neck therebetween, one of said members having openings to receive said gudgeons and said members having similar circumferential discharge slots adapted to register with the slot of the neck when the cap is extended by the displacement of the contents of the tube, and means for automatically returning the cap to the closed position. 100

3. A collapsible tube having a normally open neck, said neck having a circumferential discharge opening, a cap for closing the neck comprising concentric tubular members adapted to telescopically receive the neck therebetween, said members having similar discharge openings opposite each other, the said openings being non-communicating when the cap is in the closed position, said cap adapted to be extended by pressure exerted on the body of the tube 110 for bringing the discharge openings of the neck and cap into registry radially, and means for automatically returning the cap to closed position when pressure on the body is relaxed. 115

4. A collapsible tube having a normally open neck, said neck having a lateral discharge opening and having gudgeons below said opening, a cap for closing said neck, said cap comprising concentric tubular members which are spaced to receive therebetween the said neck, one member of said cap having L-shaped slots for receiving said gudgeons, said members having lateral discharge openings adapted to reg- 125 130

- ister with the opening in the neck when the cap is extended by the displacement of the contents of the tube, and tension means engaging said gudgeons and the said cap for automatically moving the cap towards the closed position for stopping the discharge of the contents of the tube through said openings.
5. A pliable tube having a normally open neck, said neck having a laterally disposed slot for the discharge of the contents of the tube when the tube is squeezed, and having outwardly projecting radial pins, a cap for closing the neck, said cap comprising concentric tubular members which are spaced to slidably receive the neck, said members having corresponding lateral discharge slots adapted to register with the discharge slot of the neck when the cap is moved away from the body of the tube by the displacement of the contents, means for automatically moving the cap towards the body for stopping the discharge through said slots when the pressure on the tube

- is relaxed; and means for locking the cap against accidental longitudinal movement.
6. A collapsible tube for tooth-paste and the like comprising a pliable body and a normally open tubular neck, the latter having a discharge slot in one side, a telescoping cap for closing the open end of the neck, said cap having similar discharge slots arranged opposite each other adapted to register with the slot in the neck when the cap is moved longitudinally away from said body, said cap having L-shaped slots near its open end, radial pins carried by the neck and engaging said L-shaped slots for permitting the extension and also the partial rotation of the cap on the neck, means for preventing accidental release of the cap, and tension means for moving the cap towards the body of the tube for moving the discharge slots of the cap out of registry with the discharge slot of the neck.

In testimony whereof I affix my signature.

MARTIN L. BYRNE.
